UNITED STATES PATENT OFFICE.

WALTER ANDREW BLAIN AND WILLIAM C. BELL, OF BLACKSTOCK, SOUTH CAROLINA.

REVERSIBLE ROTARY-DISK PLOW.

SPECIFICATION forming part of Letters Patent No. 651,522, dated June 12, 1900.

Application filed October 2, 1899. Serial No. 732,359. (No model.)

To all whom it may concern:

Be it known that we, WALTER ANDREW BLAIN and WILLIAM C. BELL, citizens of the United States, residing at Blackstock, in the 5 county of Chester and State of South Carolina, have invented certain new and useful Improvements in Reversible Rotary-Disk Plows, of which the following is a specification.

Our invention is a reversible rotary-disk 10 plow; and it consists in the novel construction and arrangement of its parts, as herein-after set out in this specification and the claims thereunto attached.

In the accompanying drawings, Figure 1 is 15 an elevation of our invention. Fig. 2 is a longitudinal sectional view of our invention. Fig. 3 is a longitudinal top plan view of the same. Fig. 4 is a perspective view of the guide-piece 44 and of the horseshoe-shaped 20 locking device 45, secured on the upper face thereof. Fig. 5 is a bottom plan view of the bearing 50 and of the short horseshoe-shaped block 52, secured on the lower face thereof.

Our invention may be described as a machine 25 mounted on three wheels—two front wheels and a rear wheel as a trailer or guide-wheel. The front wheels are mounted on an axle and provided with a tongue to which the team may be attached. The front end of a 30 plow-beam is mounted on the top of the tongue in such a manner that the front end of it may be raised or lowered, and thus the disk plow may be sunk deep, trail in the ground, or may be raised entirely out of the ground. 35 The front end of this beam is pivoted to the front axle, so that said axle and its tongue may be to a limited extent freely turned to the right or to the left. Extending downwardly from this plow-beam is a bearing in 40 which is pivoted the plow-foot, and on this plow-foot is journaled a disk plow, which freely rotates. Also to the foot is secured a yoke-shaped brace, and to each end of said brace is secured a disk-cleaner. This plow- 45 foot is pivoted or journaled in its bearing, and it is connected to a lever, so that the plow-foot and disk may be turned either to the right or to the left. The trailer or guide-wheel is journaled in a bifurcated bearing, so 50 that it may also turn freely. The front end of this bearing is journaled in a cylindrical

bearing, so that it may be turned over to the right or to the left, and thus incline the guide-wheel. The cylindrical bearing has a projection which passes downwardly through a slot, 55 by which the rear end of the bifurcated bearing may be turned to the right or to the left, and to the front end and above the cylindrical bearing is a means for locking the said bifurcated bearing against axial rotation. 60

Our invention is described as follows, similar numerals of reference referring to similar parts throughout the several views.

In Fig. 1 the right front wheel is left off, so that the coupling may be better shown. 65

1 represents the front axle; 2, one of the loops by which said axle is secured to the tongue; 3, one of the front wheels; 4, the tongue.

5 represents a strap or housing for the beam 70 10, secured to the tongue by bolts 6. The platform 7 of this strap or housing is provided with rear and front perforations at the points indicated by the figures 8 and 9. The beam 10 has in its front end a vertical perforation at the point indicated by the figure 11, and in front of this perforation is a vertical slot 12. (See Fig. 3.) Running through the perforations 8 and 11 is a bolt 13, having two heads 14 and 15, the first above and the second below the platform 7. A pin 16 passes through the perforation 9 and the slot 12. Thus the tongue 4 and the axle 1 are allowed to turn to the right and to the left only to a limited degree, being arrested by the end 85 walls of the slot 12 when the said axle is turned a certain distance either way.

Secured to the front end 17 of the beam 10 is the lower end of the loop 18, the upper part of the loop passing over the platform 7 90 of the elevator 5. To this loop is pivoted the short arm of a bell-crank lever 19, the fulcrum-bolt 20 being pivoted to a bearing 21, secured to the upper face of the platform 7 of the elevator 5. Thus by moving the free 95 end of said lever 19 forward or backward the front end of the plow-beam 10 may be raised or lowered to the extent of the distance between the upper face of the front end of said beam and the lower face of the shoulder 15. 100 Midway, the beam 10 is provided with a hollow bearing 22. This bearing may be integral

with the beam or may be secured thereto in any substantial way. Below and impinging against the lower end of this hollow bearing 22 is a plow-foot 23, having a cylindrical rod 24 passing up through the hollow bearing 22, the upper end 25 of which, however, is square.

To the front face of the plow-foot 23 is pivoted a rotary plow-disk 26, and to the front face of the foot 23 and just behind the 10 disk is secured an iron bar 27, terminating in arms 28, and to the front ends of these arms is secured a disk-cleaner 29. This disk-cleaner consists of a sheet of metal, its lower edge nearly impinging against the front face 15 of the plow-disk and keeping the same perfectly clean as it revolves.

To the square part 25 of the cylindrical rod 24 is secured a lever-arm 30, and to the free end of this lever 30 is hinged one end of a 20 pitman or connecting rod 31, (see Fig. 3,) the free end of which is pivoted to a lever 32. This lever 32 is pivoted at the point 33 to a bearing 34, which is rigidly secured to the tail end of the hollow bearing 22. This tail 25 end 35 of the hollow bearing extends back horizontally for some little distance and widens as it extends into a fantail, the extreme end of which is circular or curved, (see Fig. 3,) and running perpendicularly through 30 the rear end of this fantail and concentric with a pivoted bolt 36 is a slot 37. From the pivoted bolt 36 and running underneath this fantail 35 is an arm 38, and above this fantail and from said bolt 36 runs another arm 39, and these two arms are rigidly secured to 35 the said bolt 36, so that when said bolt turns to the right or left the two rear ends of these two arms also swing to the right or to the left.

To the lower end of the bolt 36 is rigidly 40 secured one end of an arm 40, and to the outer end of this arm is pivoted the rear end of a lever 41, its front end 42 being pivoted to the lower end of the lever 32, so that when the upper end of the lever 32 is pushed forward 45 the disk is turned to the left, the outer end of the arm 40 is pushed back, which throws the rear ends of the upper and lower arms 38 and 39 to the left, the front end of the turning device 44 to the left, while its rear end 50 inclines to the right. This movement throws the rear guide-wheel in such position as inclines it to run to the left, while it is, in fact, standing on a line with the beam 10. When the upper end of said lever 32 is pushed to 55 the rear, it throws the disk to the right, the outer end of the arm 40 is pushed forward, which throws the rear ends of the upper and lower arms 38 and 39 to the right, the front end of the turning device 44 to the right, 60 while its rear end inclines to the left. This movement throws the rear guide-wheel in such position as inclines it to run to the right, while it is, in fact, standing on a line with the beam 10. The rear ends of these arms 38 and 65 39 are each provided with vertical perforations 43.

Pivoted on the upper face of the upper arm

39 is the turning device 44, having secured to its upper face and front end a horseshoe-shaped locking device 45. This turning device 70 consists of a plate having a front circular end and having in its center a perforation, a rear guide-piece 46, having its central part cut away, leaving a curved back part 47, and two side arms 48. Pivoted to the rear end of 75 the fantail 35 is a spool 49, which works between the rear part 47 and the two side arms 48. Mounted and pivoted on the upper face of this turning device 44 is a cylindrical bearing 50, having a horizontal perforation passing through its center, and extending downwardly from its body is a circular part 51, and attached to the rear part of this circular part is a shorter circular part or horseshoe-shaped lock 52. Now when the rear end of the 80 bifurcated bearing 53, in which works the guide-wheel 54, is turned to the right the two right-hand ends of these two horseshoe-shaped devices 45 and 52 contact and keep the said wheel 54 from turning any farther to the right, 85 and when the said bearing is turned to the left the left-hand ends of these horseshoe-shaped devices contact and keep said wheel from turning farther to the left. Thus it may be said that at a certain angle to the right the 90 said bifurcated bearing 53 is locked and at a certain angle to the left it is locked. The normal position of this wheel 54 is perpendicular, and there is attached to and extending from the front end and upper part of the 95 cylindrical bearing 50 a segment-rack 55, and secured to the front of a square part 56 of the bifurcated bearing 53 is an arm 57, having 100 on it a locking device 58, the lower end of which sinks in the notches of the part 55, 105 and thus the top part of the guide-wheel 54 may be inclined to the right or to the left.

Rigidly secured to the lower part of the cylindrical bearing 50 is a bolt 43', which passes down through a perforation in the 110 rear part of the arm 39, the slot in the fantail part 35, and the perforation in the lower arm 33. On this bolt working in said slot is a spool 60 to prevent friction.

The rear end of the arm 38 is secured from 115 falling out of its place by a nut 59.

The turning device 44, its rear end working over the spool 49, allows the bearing 53 to turn at right angles to the main body of the machine in order that the driver may 120 make a short turn. Thus it will be seen that this plow is especially adapted to plow where we have to make quick turns either around hilly places or stumps or other obstruction and where we have to turn short at the ends 125 of the rows and is particularly adapted to plow on the side of a hill, because by shifting the disk from one side to the other we can all the time throw the cut by going back and forth in the same cut, up the hill, or we may 130 do the same on level ground, thus avoiding the necessity of having to lay the ground off in "lands."

Having described our invention, what we

claim as new, and desire to secure by Letters Patent, is—

1. In a disk plow the combination of the front part of the frame mounted on the axle-
5 wheels, having means as described for elev-
ating the front end of the beam; the hollow
bearings extending downwardly from the
said beam; the plow-foot pivoted in said bear-
ing; the disk pivoted on the front part of
10 said bearing, with a lever adapted to throw
said disk to the right and to the left, and the
rear mechanism as described, adapted to turn
the rear wheel to the right or to the left,
substantially as shown and described and for
15 the purposes set forth.

2. In a disk plow the combination of the front axle and wheels, the beam pivoted to
said front part and adapted to be raised and
lowered by a lever; the disk journaled on a
20 foot, pivoted in a bearing secured to the said
beam; the tail part extending from the rear
end of the bearing and widening into a fan-
tail; a bearing pivoted above the upper face
and rear end of said fantail, its rear end
25 adapted to be turned to the right or to the
left by levers and arms substantially as
shown; a bifurcated arm journaled in said
bearing and adapted to be turned to the
right or left, and locked in position by a lock-
30 ing device; a guide-wheel journaled in the
rear end of said bearing, substantially as
shown and described and for the purposes
set forth.

3. In a disk plow the combination of the
35 front axle, wheels and tongue; the housing
secured to the tongue; the plow-beam, its
front end pivoted between the said tongue and
the housing; a lever mounted on the housing
40 and adapted to raise and lower the front end
of said beam; a bearing vertically perforated
and extending downwardly from the said
beam; a foot pivoted in said bearing; a cir-
45 cular disk journaled to the front face of said
foot; a fantail part extending from the rear
part of the bearing and having in its rear end
a lateral curved slot and on the upper face of
its extreme rear end journaled a spool; arms
50 pivoted nearly midway between the ends of
said fantail, their rear ends perforated so as
to register with said slot; a turning device con-
sisting of a part having a perforation through
its front end, and its rear end consisting of a
55 rear curved part and two arms, all integral
with the front part; a horseshoe-shaped lock-
ing device mounted on the front end of said
piece; a cylindrical bearing pivoted over the
slot in the fantail, the perforations in the
arms and the perforation in the turning de-
vice, and having at its rear end a short horse-
60 shoe-shaped locking device, its ends adapted
to contact with the ends of the horseshoe-

shaped locking device on the turning device
just described; a bifurcated bearing having
its front end pivoted in the bearing just de-
scribed and adapted to be turned to the right
65 or to the left and held in position by a lock-
ing device, substantially as shown; the guide-
wheel pivoted in the rear end of the last-men-
tioned bearing, substantially as shown and de-
scribed and for the purposes set forth.

70 4. In a reversible rotary-disk plow as shown;
a pivoted plow-foot; a rotary disk pivoted to
the front face of the plow-foot; a bar secured
to the front face of the plow-foot and termi-
nating in arms; a cleaner secured to said arms,
75 and standing immediately in front of said disk
and adapted to clean the front face of the
same as it rotates, substantially as shown and
described and for the purposes set forth.

80 5. A reversible rotary-disk plow, consisting
of the front axle 1, front wheels 3, tongue 4
mounted on said axle; housing 5, having a
platform 7, mounted on said tongue; a bear-
ing mounted on said platform and carrying a
lever; a loop 18, secured to the short end of 85
the said lever and to the front end of the plow-
beam 10 and adapted to raise and lower the
same; plow-beam 10 its front end pivoted
above the axle 1; vertically-perforated bear-
ing 22, secured to the beam 10 and extending 90
downwardly; plow-foot 23, journaled in said
bearing and adapted to be turned to the right
or left by an arm 30; disk 26, journaled to the
front face of the plow-foot 23; lever 32, adapt-
ed to operate the plow-foot 23 and arm 41; 95
tailpiece 35, extending from the rear part of
the bearing 22, and having in its rear end a
slot 37, and on the upper face of said rear end
a spool 49; arms 38 and 39, their front ends
pivoted nearly midway to tailpiece 35, their 100
rear ends perforated; a rod 43, passing up
through the perforations in said arms 38 and
39, through the slot 37 and through the per-
foration in the guide and locking device; a
guide and locking device 45 as described, 105
working on the upper face of the arm 39 and
its rear end over the spool 49; guide 50, se-
cured to the upper end of said rod, having a
locking device 52; a bearing 53, its front end
110 journaled in the bearing 50, and adapted to
be locked in position by a locking device 58;
wheel 54, journaled in the rear end of bear-
ing 53, substantially as shown and described
and for the purposes set forth.

115 In testimony whereof we affix our signa-
tures in presence of two witnesses.
